UNITED STATES PATENT OFFICE.

GEORGE E. SHEPARD, OF JERSEY CITY, NEW JERSEY, ASSIGNOR TO HALL, NICOLL & GRANBERRY, OF NEW YORK, N. Y.

CASE FOR LAWN-TENNIS IMPLEMENTS.

SPECIFICATION forming part of Letters Patent No. 298,125, dated May 6, 1884.

Application filed February 7, 1884. (No model.)

To all whom it may concern:

Be it known that I, GEORGE E. SHEPARD, a citizen of the United States and a resident of Jersey City, in the county of Hudson and 5 State of New Jersey, have invented a certain new and useful Case for Lawn-Tennis Implements, of which the following is a specification.

My invention consists in a novel and useful 10 arrangement and construction of a case or box for containing implements used in playing the game of tennis, and has special reference to devices whereby the rackets may be firmly confined or clamped in such position when not 15 in use that twisting of the same out of shape will be prevented, and also so that when two or more rackets are confined in one case they will not rub against each other, and thus become marred. 20 In the drawings like letters refer to like parts.

Figure 1 is a plan view, looking down into the box or case, the cover being open. Fig. 2 is a side view, the side of the case and the 25 shoe-compartment being removed. Fig. 3 is a detached view of the metal pieces G shown in Figs. 1 and 2.

A is the case, made of wood, leather, metal, or other suitable material, and supplied with 30 trimmings usual in such structures. It is of the requisite length, width, and depth to contain the rackets, balls, shoes, and other things needed or desired by a tennis-player.

B is the cover, on the inside of which may 35 be kept, either in a pocket or confined by suitable straps or otherwise, the tennis shirt and trousers.

C C are two compartments adapted, respectively, to hold the balls and shoes.

40 D D are the rackets, two being shown in the drawings.

At either side of the box or case, and so placed that they will not interfere with the rackets, are metallic rods E E E E. They are 45 firmly fastened in any suitable manner at their lower ends to the bottom of the case, and stand vertically in it. F and F' are two pieces of board, made to conform in general outline to the bow part of the racket, although larger 50 than such part, so as to overlap the bow all around. The one marked F' is of such thick-

ness that when placed between the rackets they will be separated, as shown in the drawings, so that their handles will not touch each other. Both of these boards are of such size 55 that they may be conveniently dropped into place between the rods E E E E, and they are both preferably covered with flannel or other soft material, as is also the bottom of the case and the board I, so that the rackets will not 60 come in contact with any hard substance which might mar their polish.

G G are two stiff pieces of brass or other material, which are provided with recesses at or near their ends, into which the rods E E 65 pass when the pieces G are in use. Holes may be made in the ends of the pieces G instead of the recesses. In this case they will be slipped over the ends of the rods E, the thumb-screws being removed.

H H are thumb-screws, threaded as usual, the threads in which match into corresponding threads on the upper ends of the rods E E.

I is a piece of board placed in the bottom of the case, so as to give the bow of the lower 75 racket the necessary "set off" from the bottom of the case to compensate for the difference in thickness between the bow of the racket and its handle, so that no strain will come on the handle.

The operation is as follows: The lowermost racket is put into the box. Then the board F' is placed on it. Then the second racket is placed in on top of the board F'. Then the second board, F, is placed in position. Then the 85 pieces of metal G are slipped under the thumb-screws, and then the thumb-screws are turned down until the boards and the rackets are rigidly clamped together, and held down upon the bottom of the box; and, since the lower 90 racket rests on the flat bottom board, I, and the boards F' and F are also flat, the bows of the rackets are held, as it were, in a vise or clamp, and cannot twist or bend out of shape, as they are apt to do when placed in an ordinary cloth or leather covering, especially if the catgut and the bow have become wet prior to being placed in such covering.

I do not limit myself to the precise construction of the devices shown, since they may be 100 considerably varied and yet the advantages of my invention be secured. Nor do I con-

fine myself to the combination of two rackets with the other devices shown, since my invention is applicable to one racket or more than two.

5 Having described my invention, I claim—

1. The combination of the case A, the rods E, the boards I, F', and F, the metal pieces G, and the thumb-screws H, substantially as and for the purposes set forth.

10 2. The combination of the case A, the rods E, the boards F' and F, the metal pieces G, and the thumb-screws H, substantially as and for the purposes set forth.

3. The combination of the case A, the rods

E, the board F, the metal pieces G, and the 15 thumb-screws H, substantially as and for the purposes set forth.

4. The combination of the case A, the rods E, the metal pieces G, and the thumb-screws H, substantially as and for the purposes set 20 forth.

Signed at New York, in the county of New York, and State of New York, this 6th day of February, A. D. 1884.

GEO. E. SHEPARD.
